UNITED STATES PATENT OFFICE.

JAMES J. SKINNER, OF FLINT, MICHIGAN.

DESIGN FOR A BOOKHOLDER.

Application filed December 22, 1923. Serial No. 8,122. Term of patent 14 years.

To all whom it may concern:

Be it known that I, JAMES J. SKINNER, a citizen of the United States of America, residing at Flint, in the county of Genesee and State of Michigan, have invented a new, original, and ornamental Design for a Bookholder, of which the following is a specification, reference being had to the accompanying drawings, forming a part hereof.

The figure is a perspective view showing my new, original and ornamental design for a book holder.

I claim:

The ornamental design for a book holder as shown.

JAMES J. SKINNER.
